(57) **CLAIM**

The ornamental design for an inversion table stand, as shown and described.

DESCRIPTION

FIG. 1 is a perspective view of an inversion table stand showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof, with the inversion table engaged.

The broken lines showing an inversion table illustrates environmental structure and forms no part of the claimed design.
